Robert B. Karoff, New York, N. Y., assignor to
Novelty Utilities, Inc., New York, N. Y., a corporation of New York

Application May 6, 1952, Serial No. 19,610

Term of patent 14 years

(Cl. D44—3)

To all whom it may concern:

Be it known that I, Robert B. Karoff, a citizen of the United States and a resident of New York city, county and State of New York, have invented a new, original, and ornamental Design for a Combined Foldable Roast Board and Food Tray, of which the following is a specification, reference being had to the accompanying drawing, forming a part thereof, in which:

Fig. 1 is a perspective view of a combined foldable roast board and food tray showing my new design in open condition;

Fig. 2 is a vertical cross-sectional view taken on line 2—2 of Fig. 1;

Fig. 3 is a perspective view showing the article in closed condition; and

Fig. 4 is a bottom plan view thereof.

I claim:

The ornamental design for a combined foldable roast board and foot tray, as shown.
ROBERT B. KAROFF.
